(57) **CLAIM**

The ornamental design for a hang caddy, as shown and described.

DESCRIPTION

FIG. 1 is a perspective view of a hang caddy according to my new design;

FIG. 2 is a front view of the embodiment illustrated in FIG. 1;

FIG. 3 is a back view of the embodiment illustrated in FIG. 1;

FIG. 4 is a side view of the embodiment illustrated in FIG. 1;

FIG. 5 is an opposite side view of the embodiment illustrated in FIG. 1;

FIG. 6 is a top view of the embodiment illustrated in FIG. 1; and,

FIG. 7 is a bottom view of the embodiment illustrated in FIG. 1.

The broken lines shown in the drawings depict portions of the hang caddy that form no part of the claimed design.

1 Claim, 7 Drawing Sheets
